APPARATUS FOR WRAPPING CIGARS

Martin Berger, Freital, Germany, assignor to
 "Universelle" Cigarettenmaschinenfabrik, J. C.
 Muller and Co., Dresden, Germany

Application September 3, 1931, Serial No. 561,080
 In Germany December 1, 1930

14 Claims. (Cl. 93—6)

The present invention relates to the packing of cigars, by mechanical means, in individual coverings of tissue paper, cellophane or the like. It is known that cigars of particularly high quality have been provided with separate coverings in order to preserve the aroma of the cigar as satisfactorily as possible. These coverings have hitherto been made by hand, which is relatively expensive.

- 10 The present invention renders the covering of cigars considerably cheaper by means of the relative movement between a reciprocating spoon which receives the cigars and a tube or tube portion of tissue paper, "Cellophane" or the like
 15 which is moved towards said spoon, the cigars being thrust into the tube portion separated previously or at this juncture from the tube, and the said tube portion being then closed by twisting its ends together by mechanical means.
 20 The covering, which is formed round a core, is preferably thrust by means of conveyer rollers onto a spoon, by which the cigar is inserted into the covering.

Further, the cigar resting in the spoon-carrier
 25 is suitably conveyed by means of an actuated finger into the covering resting on the spoon. The covering removed from the spoon and containing the cigar is then suitably deposited on a grooved drum provided with folding fingers, rotating sleeve or the like, by means of which the ends of the covering are folded or twisted together.

The figures in the accompanying drawings serve to illustrate the invention.

- 35 Figs. 1 and 1a show a general view of the apparatus.

Figs. 2 and 3 show a plan thereof in two different operative positions.

Figs. 4-7 show detailed views.

- 40 Fig. 4 shows the part of the drum in the range of which the ends of the cigar covering are closed.

Fig. 4a shows the folding device therefor.

- 45 Figs. 5 and 6 show a closing device, resembling a rotating sleeve in two operative positions.

Fig. 7 shows a side view of the closing device.

Fig. 8 shows another apparatus for closing the ends of the coverings.

- 50 Fig. 9 is a partial side view of the construction of Fig. 8.

Figure 9a is a continuation of the showing in Figure 9.

Figure 10 is an enlarged lateral elevation of the perforating device.

- 55 Figure 11 is an enlarged partial side elevation

of the folding fingers showing the adhesive applying devices, and

Figure 12 is a side view of the showing in Figure 11.

The paper strip 2 coming from the bobbin 1 is passed over the rollers 3 and the tension device 4 to a conical core 5, after it has been provided at 6 with printing or the like. The paper strip is formed on the core into a covering which is closed at 6' by means of an adhesive or pressure. 10 Near the end 5' of the core 5 the cutting device 6" is arranged which divides the formed tube into individual tube sections. The separated, tube portion (covering) H is thrust by a suitably shaped pair of rollers 7, 7' onto the spoon 8 which is held ready. When the covering is thrust onto the spoon 8, the latter is in the position indicated in Fig. 2. The cigar Z is in the hollow space of the spoon 8. In the position shown in Fig. 2, the covering has been thrust onto the spoon 8, 20 and the finger 9 which is mounted on the lever 11 pivoted at 10 is moved downwards by the cam 12. The finger 9 hereby engages in a groove 13 provided on the spoon 8. If the spoon 8 then passes to the left, according to Fig. 1, the 25 sheath H together with the cigar Z is stripped from the spoon. The sheath H containing the cigar falls into the trough of the drum 21 in readiness therefor, and which is described hereinafter. The connecting rod 14 which moves 30 the spoon holder 18 on the rails 19, is connected at 15 with a crank arm 16. While the cigar with the covering is removed, the rear part of the spoon 8 passes over a conveyer belt 17 having grooves 17' containing cigars, on which the cigars 35 are passed in the direction indicated by the arrow in Fig. 2, until they come within the range of the spoon 8. When the spoon 8 has removed the cigar from the conveyer belt 17, it returns to the position shown in Fig. 2 and again takes up a covering and the operation recommences.

Thus, after they are removed from the spoon 8, the covering containing the cigar falls into the groove 21' of a grooved drum 21. This drum is moved intermittently by any desired mechanism and first of all passes the coverings in front of a ram 22, which is actuated by a rocking lever 24 mounted at 23. The roller 25 of the rocking lever co-operates with a cam 26. As soon as a covering has arrived in front of the ram 22, the latter is thrust by the cam 26 into the covering, whereby the cigar arrives in the position shown in Figs. 1-3. During this process, the coverings are prevented from slipping by a stop-bar 27 which co-operates with the grooved drum 21. 50 55

After the cigar has been brought into the middle of the covering, it is first brought into the range of a finger 28 operating radially to the drum 21, which finger first of all folds the end of the covering in the manner shown in Fig. 4. After a further movement of the drum, the end of the covering arrives in front of a folding-finger 29 which performs a further folding. Then the end of the covering passes into the range of a further folding-finger 30, which folds another piece of the end of the covering. The end of the covering is then finally folded by means of the finger 31, after the drum has made another turn in the direction indicated by the arrow in Fig. 4. While the ends of the coverings containing the cigars are closed by the folding fingers 28-30, they are held by the rails 32— which are arranged parallel to the periphery—in such manner that the covering cannot turn in the grooves 21'.

Fig. 4a is intended to illustrate the means for driving the folding fingers 28-31. The folding finger 28 is mounted on a bolt 71 attached at 70 to the frame of the machine. To the finger 28 there is connected the lever 72 at the end of which a toothed quadrant 73 is provided. The toothed quadrant engages with a rack 74 which is mounted in suitable recesses 75 of the machine casing 76. On the rack 74 a lever 78 engages by way of a link member 77, which is swivelled by actuating members not shown in such manner that the rack is drawn downwards at the right moment into the position shown in Fig. 4. The folding finger 29 is mounted at 79 on the machine casing 76 and carries a toothed quadrant 80 which engages with the rack 74 by means of a spur wheel 82 mounted on the machine frame at 81. The folding finger 30 is mounted at 83 on the machine frame and also carries a toothed quadrant 84 which engages with the rack 74. The folding finger 31 is mounted at 85 on the machine casing and also engages with the rack 74 by means of a toothed quadrant 86 with which it is provided.

Thus, when the rack 74, actuated by the lever 78, passes into the position indicated by dotted lines in Fig. 4a, the folding fingers 28-31 are swung back whereupon the drum 21 can make a further movement, and the folding fingers 28-31 can again come into operation.

It is obvious that before the fingers 28-30 come into contact with the ends of the covering, they can be caused to pass over a device which supplies glue, so that adhesion is effected simultaneously with the folding operation. For each finger there is provided a cement applying roller 100 which is connected to an adhesive receptacle 101. When the fingers 28, 29, 30 and 31 swing out they make contact with the corresponding adhesive devices and take off a thin layer of adhesive which they give off when folding the corresponding flaps. Only certain of these adhesive applying devices are shown in the drawings, but the remainder are similar in construction.

The folding fingers 28-31 can, however, also be arranged advantageously only on one side of the drum, while on the other side of the drum the apparatus for closing the end of the covering facing the tip of the cigar, shown in Figs. 5-7, is arranged. Figs. 5 and 6 show a longitudinal section of this apparatus in various operative positions. Fig. 7 shows a partial view of the apparatus shown in Fig. 6, as seen from the left. This apparatus resembling a rotating sleeve consists of a sleeve 33 which is preferably adapted to be

displaced longitudinally in relation to the end of the covering which is opposite the folding finger 28. On the sleeve 33 a further sleeve 34 is mounted, the conical end 34' of which engages under the rear ends of the pivoted levers 35. The pivoted levers 35 are articulated at 36 to the sleeve 33 and their front ends 35' engage in the holes 37 of the cheeks 38. While the folding finger 28 closes the end of the covering in the manner shown in Fig. 4, the sleeve 33 is thrust onto the other end of the covering in such manner that the cheeks 38 assume the position shown in Fig. 5. By means of a controlled lever 40 engaging in the annular groove 39, the sleeve is displaced in such manner that the cheeks arrive in the position shown in Fig. 6. As the sleeve 33 is mounted on a continually rotating spindle, the end of the covering is twisted together in the manner shown in Fig. 6. It is obvious that if the rotating sleeve is not so arranged, that it moves with the grooved drum 21, it must perform this operation in the same time that is required by one of the folding fingers to complete its folding operation.

Further it is immaterial whether the rotating sleeve shown in Figs. 5-7 performs its function simultaneously with one of the folding fingers 28-30 or if the twisting together of the end of the covering takes place before or after this operation.

Under the grooved drum 21 there may be arranged advantageously a conveyer belt 42 running over the rollers 41, which belt passes the cigars, covered in the manner just described, to the position where they can be further dealt with (packing position).

In the mode of construction shown in Figs. 8 and 9 the grooved drum 21 is not provided with folding devices for folding the ends of the covering. The coverings containing the cigars are thus transferred from the drum to the conveyer belt 43 without closing them. The conveyer belt 43 provided with the troughs 43' is provided with two pairs of rollers 44 and 45, which squeeze the two ends of the covering together. The end of the covering facing the tip of the cigar is now conducted to a perforating device 46. The vertically reciprocating punch 47 cooperates with a suitably formed matrix 48 which serves as a bearing or support for the squeezed-together ends of the sheath. The punch 47 thereby carries a series of punching dies 47' opposite which are corresponding openings in the matrix 48. The punch 47 is moved vertically in the guides 47', which are provided on the frame portion 47", the matrix 47" is also secured to the frame portion 43. The punch 47 is provided with a slot 47", in which the crank pin 47" engages. The crank pin 47" is mounted on the crank (cam) disk 47" which is mounted on the shaft 47". Also mounted on shaft 47" is the sprocket wheel 47" which is connected by means of the chain 47" with the sprocket chain mounted on the squeezing device 44, 45.

After two further movements of the conveyer belt, the coverings arrive in the range of the device V, by means of which the ends of the covering are provided with the adhesive tabs. The adhesive tabs are made from the paper strip 49 coming from the bobbins 50. The pair of rollers 51, which are driven by the Geneva gear 52, serve as tension members. Behind the pair of tension rollers 51 there are arranged the glue-applying rollers 53, which are connected with the glue-container 54. The rollers 55 serve

as abutment for the rollers 53. As soon as the strips have arrived in the position shown particularly in Figs. 8 and 9, in which the ends rest on small tables 56 and the flattened ends of the covering rest thereon, the knives 57, which are pivoted on pins 58, are swung in the direction indicated by the arrow in Fig. 9. Thus the edges of the knives 57 meet with the edges of the knives 59, so that a short portion is always separated from the strip 49. The pivoting movement of the knives 57 is produced by means of the spur wheels 60 which are oscillated by the crank mechanism 61, 62. With the spur wheels 60 there engage the toothed quadrants 63 which are connected with the axes 58 of the knives 57. Now when the tabs have been severed, the knives swing further into the position indicated by dotted lines in Fig. 9, in which they place the previously severed ends of the tabs on the already adhering ends of the flattened end portion of the covering. Then the knives swing back into their initial position, and the conveyer belt 43, after the tab-strips 49 have again been advanced, can bring the next covering into the range of the small tables 56. The conveyer belt 43 then carries the covering—closed in the manner just described and containing the cigar—to the packing position. It should be added that the conveyer rollers 51 are connected with the gluing rollers 53 by a toothed wheel gear 64.

Having thus described the nature of the said invention and the best means I know of carrying the same into practical effect, I claim:

1. A wrapping machine comprising means for continuously feeding a strip of flexible material, means for forming said strip into a tube, means for cutting said tube into predetermined lengths, means for feeding said lengths to a filling station, means for inserting a cigar into said lengths while at said filling station by carrying the cigars therein and means for stripping said cigars from said inserting means so as to deposit said cigars within said lengths.

2. A wrapping machine comprising means for holding a tube of flexible material, a reciprocating spoon for inserting articles within said tube, cam operated mechanism for stripping said articles from said spoon and depositing the same within said tube, cam operated mechanism for adjusting the position of said articles within said tube and means for sealing the ends of said tube to enclose said articles within said tube.

3. A wrapping machine comprising a magazine for a continuous strip of flexible material, means for feeding said strip from said magazine, means for printing upon said strip, core means for forming said strip into a continuous tube, means for cutting said tube into predetermined lengths and means reciprocating in a direction parallel to the movement of said tube for carrying articles within said lengths.

4. A wrapping machine comprising means for forming a continuous tube of flexible material, means for cutting said tube into predetermined lengths, a spoon carrying an article to be wrapped, means for feeding a predetermined length of tube over said spoon, means for stripping said article and said length from said spoon, a drum having grooves therein into which said length and article is moved and means for sealing the ends of said lengths while carried by said drum.

5. A wrapping machine comprising means for forming a continuous tube of flexible material, means for cutting said tube into predetermined lengths, an endless belt intermittently operated

carrying the articles to be wrapped, a reciprocating spoon for taking said articles from said belt and inserting the same within said predetermined lengths means for withdrawing said spoon from said lengths and means for closing the ends of said lengths in order to enclose said articles.

6. A wrapping machine comprising a rotary drum having grooves therein in which tubes of flexible material are held, article feeding means located adjacent said drum, means for transferring an article from said article feeding means into said tubes held in said drum and a reciprocating ram for adjusting the position of said article within said tube.

7. A wrapping machine comprising a rotary drum having grooves therein in which tubes of flexible material are held, article feeding means located adjacent said drum, means for transferring an article from said article feeding means into said tubes held in said drum, a reciprocating ram for adjusting the position of said article within said tube and means for closing the ends of said tubes to enclose said article.

8. A wrapping machine comprising a conveying device carrying tubes of flexible material having articles therein, means for compressing the ends of said tubes, a perforating device for providing a separating seam and means for applying a tab upon the flattened ends of said tubes.

9. A wrapping machine comprising means for forming a continuous tube of flexible material, means for cutting said tube into predetermined lengths, means for inserting articles to be wrapped into said lengths, means for conveying said lengths with the articles therein, means for compressing the ends of said lengths, perforating means for providing a separating seam at the compressed ends and means for applying a glued tab upon the flattened ends of said lengths.

10. A wrapping machine comprising means for forming a continuous tube of flexible material, means for cutting said tube into predetermined lengths, conveying means, means for feeding said lengths to said conveying means, means for inserting articles to be wrapped within said lengths while at said conveying means, rollers for compressing the ends of said lengths while carried by said conveying means, means for feeding the continuous strip of material for tabs, means for cutting said tab material into predetermined lengths, means for applying adhesive to said tabular material and means for applying said tabs to the ends of said lengths.

11. A wrapping machine comprising means for conveying a tubular length of flexible material with articles therein, means for flattening the ends of said lengths, means for feeding a continuous strip of tab material to a position adjacent said conveyor and means simultaneously cutting predetermined lengths of tab material from said strip and applying the same to the ends of said lengths.

12. A wrapping comprising a conveyor carrying articles within tubular sheaths, means for intermittently feeding a continuous strip of tab material towards said conveyor, means for applying adhesive to said strip, a fixed cutting blade located above said strip of material, a pivoted cutting blade located below said strip of material and means for oscillating said pivoted cutting blade to cooperate with said fixed blade to cut said tab material into predetermined lengths and at the same time apply said tab material to the ends of said sheaths.
